US00D930703S

(12) United States Design Patent (10) Patent No.: US D930,703 S
Mast (45) Date of Patent: * Sep. 14, 2021

(54) DISPLAY SCREEN WITH GRAPHICAL USER INTERFACE

(71) Applicant: Lean Basketball Analytics, LLC, Avon, OH (US)

(72) Inventor: Christopher Mast, Avon, OH (US)

(73) Assignee: Lean Basketball Analytics, LLC, Avon, OH (US)

() Term: 15 Years

(21) Appl. No.: 29/551,284

(22) Filed: Jan. 12, 2016

(51) LOC (13) Cl. 14-04

(52) U.S. Cl.

USPC D14/493; D14/486; D14/492

(58) Field of Classification Search

USPC D14/485-495

CPC B61C 11/04; B64C 29/00; G06F 3/04817

(57) CLAIM

The ornamental design for a display screen with graphical user interface, as shown and described.

DESCRIPTION

The single FIGURE is a front view of a display screen or portion thereof with graphical user interface showing my new design.

The dash-dot-dash lines at the perimeter of the FIGURE illustrate a display screen, and the remainder of the broken lines illustrate portions of the graphical user interface.

None of the broken lines form part of the claimed design.

1 Claim, 1 Drawing Sheet
